Letters Patent No. 2481. Date Oct. 2. 1866.
Design for a Coffin Handle.

The Schedule referred to in this Letters Patent and Making part of the same

To all whom it may concern:

Be it known that I, Charles A. Reiberg of New Haven in the County of New Haven and State of Connecticut have invented a new Design for Coffin Handles; and I do hereby declare the following when taken in connection with the accompanying drawings and the letters of reference marked thereon, to be a full, clear and exact description of the same, and which said drawings, constitute part of this Specification and represent a front view.

My invention relates to a Design for the ornamental handles

such as are used upon Coffins and the Design consists in the peculiar configuration of the socket plates, the socket forming a base supporting a central pointed gothic arch b, supported upon either side by other gothic arches c, and below the sockets inverted gothic pinnacles in relief corresponding to the gothic arches above, together forming the plate by which the socket is secured to the coffin or to whatever it is to be attached.

That I claim as my invention, is the Design as illustrated and herein described.
